UNITED STATES PATENT OFFICE.

HENRY B. DIERDORFF, OF COLUMBUS, OHIO, ASSIGNOR TO THE LECHNER MANUFACTURING COMPANY, OF SAME PLACE.

MINING-MACHINE.

SPECIFICATION forming part of Letters Patent No. 684,353, dated October 8, 1901.

Application filed April 2, 1886. Serial No. 197,558. (No model.)

To all whom it may concern:

Be it known that I, HENRY B. DIERDORFF, a citizen of the United States, residing at Columbus, in the county of Franklin and State 5 of Ohio, have invented certain new and useful Improvements in Mining - Machines, of which the following is a specification, reference being had therein to the accompanying drawings.

10 Figure 1 is a plan view of my improved machine. Fig. 2 is a rear view. Fig. 3 is a vertical section on line α α , Fig. 1. Fig. 4 is a section of the nut and its adjacent parts detached.

15 My improvements relate chiefly to the means for advancing the cutter-bar into and withdrawing the same from the coal, as will be explained.

For convenience in illustrating my invention 20 I have shown it applied to a machine which in many of its details of construction is similar to those now commonly in use.

Referring to the drawings, A A are the side pieces of the stationary frame or bed and are 25 commonly called by me "channel-bars," because of their being provided upon their inner faces with channels or grooves to receive and support T-bars B B, to be hereinafter more particularly described. These channel- 30 bars are connected with each other and supported at suitable distances apart by means of girths C C' with an additional girth or tie C² at the rear end of the machine and when desired a corresponding one at the front end 35 thereof, the girths being securely bolted to the channel-bars at suitable intervals. As indicated in Fig. 2, blocks c c are formed upon the lower members C of the girths to furnish additional supports for the channel-bars. As 40 shown in Fig. 1, the central girth has its end portions cut off even with the upper surface of the channel-bars.

The vertical webs B' B' of the T-bars fit 45 closely the grooves in the inner faces of the channel-bars, their horizontal webs b b being of such width as to facilitate the bolting thereto of many of the operative parts of the machine, such as the shaft-bearings, cross-girths, the additional braces D D, and the engines 50 or primary power devices.

E is the cutter-bar, mounted in bearings at-

tached to shoes at the forward ends of the carriage or cutter-frame.

F (see Fig. 3) is the driving-chain shaft, mounted at its ends in bearings bolted to the 55 T-bars, and F' is the driving-chain, connecting the shaft F with the cutter-bar, both of which are provided with sprocket-wheels to receive the chains.

G G are the cylinders, mounted on the carriage or cutter-frame, which consists of the T-bars and the girths and braces bolted thereto. 60 H is the crank-shaft, carrying eccentrics h h, which are connected with the valve-stems g g by means of eccentric-rods.

For the purpose of supporting a portion of the shafting I propose to employ upright frames or vertical bearing-plates H' H', (see Fig. 3,) one on either side of the machine, bolted to the T-bars. 65

i is a pinion on the crank-shaft meshing with the spur-gear l on a secondary or intermediate shaft J, which in turn carries a pinion j, meshing with a spur-gear f on the driving-chain shaft F. 70

h' is a worm on the crank-shaft H, engaging with a worm-wheel k on feed-shaft K, which at its opposite end carries a spur-pinion k', loosely thereon. The hub of pinion k' is ratchet-faced upon one side and can be connected with shaft K at will by means of a corresponding ratchet-faced clutch K², which is splined to the shaft, but can slide thereon. 75

In order to move the carriage, I employ a mechanism comprising two threaded members, one being a cylindrical externally-threaded bar and the other a hollow internally-threaded nut which revolves around the threaded bar and is adapted to engage therewith on all sides, and one of which members is reversible and double-speeded, so that it can be utilized for effecting a slow advance of the cutters and a rapid withdrawal of them. 80

I represents a bar or shaft of the sort referred to and constitutes one of the said 85 threaded members, and the nut at M', surrounding said shaft, constitutes the other.

M is a gear-wheel mounted on the axis of the threaded shaft and engaged with the rotatable part of the carriage-feeding mechanism, it being shown as connected with the nut and adapted to move along the threaded 90

shaft. The nut is carried by the hollow or tubular shaft m , actuated by and preferably secured to the wheel M concentrically with the latter and with the shaft L . A mounting 5 is provided by the frame at N . As the nut at M' revolves in one direction it advances the cutters into the coal, the construction and arrangement of parts being such that when the engine is running in the direction indicated 10 by the arrow, Fig. 3, and the clutch K^2 is engaged with the wheel k' the advancing of the carriage and cutters occurs.

For the purpose of withdrawing the cutters from the coal I employ the following gearing: 15 Upon the counter-shaft J there is a bevel-gear O , meshing with another bevel-gear o on the recede-shaft P , which carries at its opposite end a pinion p , loosely mounted. p' is a sliding clutch splined to shaft P and 20 engaging with the ratcheted hub of spur-gear p . This gear also meshes with the wheel M , the relation of parts being such that when the engine is driven in the direction indicated by the arrow, Fig. 3, and the 25 clutch p' is engaged with the spur-gear p (the clutch K^2 being withdrawn from pinion k') the cutters and cutter-frame will be withdrawn from the coal. The feed-shaft K is mounted in bearings Q , attached to the inward-projecting rib of one of the T -bars, and the recede-shaft is mounted on bearings R , attached to the cutter-frame. S is a shipping-lever pivoted at s to a supporting-standard T , attached to the cutter-frame. This 30 shipping-lever may have forks taking into grooves in the clutches $p' K^2$, so that by a single movement of the lever the direction of travel of the cutter-frame may be reversed, and so that also both clutches may be withdrawn 35 from their respective pinions and the engine permitted to run without moving the cutter-frame in either direction on the main frame.

I do not limit myself to the specific arrangement 40 of the shafting, clutches, &c., which have been selected for illustration, as in this respect there can be modifications without departing from the invention.

It will be seen that I provide essentially a 45 prime power-shaft actuated by the engine or motor, a main power-shaft geared to the prime shaft, a chain-actuated cutting apparatus driven by the main shaft, and a carriage-moving mechanism having a feed-bar supported 50 on the bed and having a carriage-driving shaft (such as the hollow shaft M) with a rotary part (such as a nut) geared to this feed-bar, together with intermediate shafting between the main shaft and the 55 rotary carriage-feeding gear, gear-wheels loosely sleeved on said intermediate shafting, reversely-arranged clutch jaws or sections on this intermediate shafting, and means for holding the clutch-jaws out of engagement 60 with said loose wheels and for moving them into such engagement.

Prior to the date of this patent it has been

proposed to arrange the engine or motor, the prime shaft, the main shaft, and the carriage-moving gearing in a modified manner, though 70 with several of the essential features of relation and construction herein shown, and in connection with a modified form of chain-actuated cutting apparatus—that is to say, it has been proposed to secure the cutters directly to the chain and in lieu of the threaded feed-bar and nut geared thereto to employ the well-known racks and pinions and to use an electric motor, and while I do not herein 75 claim specifically such mechanisms I wish it 80 to be understood that they present some of the equivalent modified constructions and arrangements which I have above referred to.

I herein mention the fact that the two jaws or sections of the clutch are "reversely arranged," meaning thereby that they are so related to the carriage-feed mechanism that they will alternately reverse the direction of the carriage. It will be understood, of course, that these clutch jaws or sections are so arranged that there is a neutral position for both of them—that is, a position where they are both out of engagement with their opposing wheels, as otherwise the carriage would be necessarily in motion constantly in one 95 direction or the other. By having a neutral position for the clutch-jaws the carriage can be stopped at the rear end of its travel or whenever desired.

It will be understood that in the drawings 100 I have not intended to illustrate working dimensions, &c., but to present, more or less conventionally, the essential features of relationship of the several parts. A relatively short bed-frame is illustrated, but with respect to all such matters the maker can adapt the parts to accomplish any desired purpose.

With respect to the patent to Lander it has already been fully noted that his construction differs materially from that herein 110 in requiring that the gear-wheel which rotates the nut should itself be bodily moved away from one driving-gear to another one. In the present construction the gear which turns the rotary feed member is rigidly secured to 115 it and the action of reversal is effected at a distant point—namely, by means of a clutch which is supported independently of the nut or other rotary member. It is thought unnecessary to dwell upon the differences in 120 result, as they will be readily understood by those acquainted with the art.

What I claim is—

1. In a mining-machine, a stationary frame, a carriage-moving bar secured thereto, a movable frame, a motor or engine mounted on said movable frame, a main shaft arranged adjacent to and parallel with the prime power-shaft of said motor or engine and adapted to be driven thereby, a carriage-driving shaft 130 mounted on said movable frame and having a gear thereon adapted to engage with said carriage-moving bar on the bed, intermediate shafting, gearing for driving said intermedi-

ateshafting from said main shaft, gear-wheels loosely sleeved on said intermediate shafting, reversely-arranged clutch-jaws mounted to slide upon said intermediate shafting and 5 splined to rotate therewith, and arranged to engage said sleeved gears respectively when shifted, gearing actuated by said sleeved gears for actuating said carriage-driving shaft, means for normally maintaining said 10 clutch-jaws out of engagement with said sleeved gears, cutters supported upon and across the front end of the carriage, a chain for driving the cutters, and a gear mounted on said main shaft adapted to engage and 15 drive said chain-actuated cutting apparatus, as and for the purpose set forth.

2. In a mining-machine, the combination of a bed-frame, a carriage, a cutting apparatus on the carriage, a prime power-shaft, a second or main shaft, slowing-down gearing connecting the prime shaft and the main shaft, carriage-feeding mechanism having a rotary reversible double-speeded member, an intermediate power-shaft between the main shaft 25 and the rotary feed member, worm-gearing connecting the main shaft and the intermediate shaft, a gear-wheel rigid with the rotary feed member, a wheel permanently connected to said gear-wheel and mounted loosely on 30 the intermediate shaft, a clutch interposed between said worm-gearing and said loose gear-wheel whereby a relatively slow speed can be imparted to the rotary feed member for advancing the carriage, a withdrawing 35 mechanism permanently geared to the rotary feed member, and a clutch for connecting the withdrawing mechanism with the power-shafts, when the advancing mechanism is disconnected, substantially as set forth.

40 3. In a mining-machine, the combination of the bed, the carriage, the cutting apparatus on the carriage, the engine or motor, the prime power-shaft, the main shaft geared thereto, a carriage-feed mechanism having a reversible double-speeded member on the carriage engaging with a member on the bed, an intermediate shaft mounted independently of the rotary feed member and rotating on an axis parallel to that of said rotary feed member, 45 a wheel rigidly secured to the rotary feed member, a wheel on the said intermediate shaft permanently geared to and reversible with the rotary feed member, a clutch for imparting power to the last said gear-wheel to 50 move the carriage in one direction, and reversible gearing connected to the rotary feed member for driving it in the opposite direction, substantially as set forth.

55 4. In a mining-machine, the combination of the bed-frame, the cutter-frame, the carriage-moving mechanism having an externally-screw-threaded member and a hollow nut surrounding said threaded member and engaging therewith on all sides, of which carriage-moving parts one is adapted to rotate and be 60 reversed, a gear-wheel on the axis of the threaded member of the carriage-moving

mechanism, and rigidly connected to the rotatable part of such mechanism, a carriage-feeding shaft parallel to the threaded member 70 and connected by a relatively slow-moving gearing to the rotatable part of the carriage-moving mechanism, a supplemental carriage-withdrawing shaft also parallel to the threaded member of the carriage-moving mechanism, and a relatively fast-moving gearing connecting said shaft to the rotatable part 75 of the carriage-moving mechanism, substantially as set forth.

5. In a mining-machine, the combination of the bed-frame, the cutter-carrying frame, the power-shaft, a bevel-wheel driven thereby, a carriage-moving mechanism having an externally-threaded member and a hollow nut surrounding said threaded member and 80 engaging therewith on all sides, of which carriage-moving parts one is rotatable and reversible, a gear-wheel on the axis of the threaded member of the carriage-moving mechanism, and connected to the rotatable part 85 of such mechanism, a relatively slow-moving gear for feeding the cutters, and the recede mechanism having parallel to the threaded member of the carriage-moving mechanism a supplemental shaft with a 90 loosely-mounted gear-wheel, a clutch, and a bevel-wheel engaging with the aforesaid bevel-wheel whereby relatively fast motion is received from the power-shaft, and imparted to the rotatable part of the carriage-moving 95 mechanism, substantially as set forth.

6. In a mining-machine, the combination of a bed-frame, a cutter-carrying frame, the cutting apparatus on the last said frame, the continuously-rotating high-speed power-shaft, the power-transmitting devices connecting the engine to the cutters, a carriage-moving mechanism having an externally-screw-threaded member and a nut surrounding said threaded member and engaging therewith on all sides, one of which carriage-moving parts is rotatable and reversible, a gear-wheel rigidly connected to the rotatable part of the carriage-moving mechanism, and advancing with the carriage, a second gear-wheel engaged with the aforesaid gear-wheel to drive it, a continuously-rotating shaft supplemental to the high-speed power-shaft carrying the said second gear-wheel, a clutch on said shaft for rigidly connecting thereto the 110 said wheel whereby the carriage is moved in one direction, and a third rotary shaft driven by the power-shaft for moving the carriage in the opposite direction, substantially as set forth.

7. In a mining-machine, the combination of the carriage-frame, the cutters thereon, the bed-frame, the power mechanism and the carriage-moving mechanism, of the three carriage-moving wheels M , k' , and p , on separate 120 shafts, and the two-part clutch having one part on the shaft of wheel k' , and the other on the shaft of wheel p , substantially as set forth.

8. In a mining-machine, the combination of the bed, the carriage, the cutting apparatus on the carriage, the engine or motor on the carriage, the prime power-shaft, the main shaft geared to the prime power-shaft and actuating the cutting apparatus, a carriage-feed mechanism having a reversible rotary member on the carriage engaging with a member arranged longitudinally of the bed, 5 a gear rigidly secured to the rotary feed member for driving it, intermediate shafting between the main shaft and the reversible feed member, gearing on the intermediate shafting permanently connected with the driving-gear 10 fast on the rotary feed member, and two sets 15

of differently-speeded power devices supported by the intermediate shafting, one for advancing the carriage and one for withdrawing it, and a two-part clutch supported on the intermediate shafting independently 20 of the rotary feed member, for alternately connecting said two trains of power devices to said rotary feed member, substantially as set forth.

In testimony whereof I affix my signature 25 in presence of two witnesses.

HENRY B. DIERDORFF.
